UNITED STATES PATENT OFFICE.

EARNEST L. MEREDITH, OF FARNAM, NEBRASKA.

CHILD'S SAFETY-HARNESS.

1,369,456.

Specification of Letters Patent. Patented Feb. 22, 1921.

Application filed May 26, 1920. Serial No. 384,333.

To all whom it may concern:

Be it known that I, EARNEST L. MEREDITH, a citizen of the United States, and a resident of Farnam, in the county of Dawson and State of Nebraska, have invented new and useful Improvements in Children's Safety-Harness, of which the following is a specification.

My invention is a child safety harness and has as its object to provide a readily applicable harness for retaining a child in standing position in a chair, go-cart, or the like, and thereby obviating the danger of the child falling therefrom and at the same time permits free movement of the child.

Further, the invention embodies an adjustable safety harness for children which will permit free movement of the latter upon a suitable base such as a chair, go-cart, etc., and at the same time prevent the child from falling.

Another important object resides in the provision of a safety harness of this character which is of comparatively simple construction and at the same time can be produced and placed on market at a nominal cost.

With these and other objects and advantages in mind the invention consists in the novel combination of elements, arrangement of parts, and specific features to be herein-after referred to and defined in the subjoined claim.

In the drawings, a perspective of the harness is shown associated with a child in a standing position, the outline of the child being illustrated in dotted lines.

Referring to the drawing in detail, wherein like characters of reference designate like parts throughout the several views the numeral 5 designates a body encircling strap adapted to pass around the child slightly below the arms and having its ends detachably connected together at the front by a buckle or other suitable fastening.

Associated with the body encircling strap 5 is a pair of shoulder straps 6 upon each of which a pair of buckles 7 are slidably mounted and which buckles connect the shoulder straps to the body encircling strap at the front and rear respectively. The

ends of the shoulder straps 6 extending below the body encircling strap 5 a relatively great distance and are provided with buckles 8 whereby to lengthen and shorten the strap. 55 Snap-hooks 9 are carried by the extremities of these shoulder straps and are engageable with eyes or rings 10 carried by detachable straps 11 which in turn carry snap-hooks 12 engageable in rings 13 fixed to the horizontal base 14 which may be the bottom of a go-cart, chair or the like. These rings 13 are so arranged with respect to the points of connection of the shoulder straps and the body strap with each pair of straps 11 that 60 the part of the straps 8 disposed below the body strap 5 will be arranged in divergent relation at the front and rear of the child respectively when the child is in standing position as illustrated in the drawings. 70

It is to be understood that the form of my invention herein shown and described is to be taken as a preferred example of the same, and that various changes in the shape, size and arrangement of parts may be resorted 75 to without departing from the spirit of the invention or the scope of the subjoined claim.

Having thus described my invention, what I claim as new and desire to secure and 80 protect by Letters Patent of the United States is:

In a safety harness, a horizontal base, pairs of eyes mounted in transverse alignment at the opposite ends of the base, a body 85 encircling flexible element, a pair of shoulder straps, elements slidably mounted upon the shoulder straps detachably connecting the shoulder straps at the front and rear respectively to the body encircling strap 90 whereby the distance between the latter and the medial part of the shoulder straps may be regulated, pairs of flexible elements detachably connected with the eyes and detachably connected between the latter and 95 the extremities of the shoulder straps, said flexible elements and the lower portions of the shoulder straps being arranged in diverging relation when the child is in standing position.

EARNEST L. MEREDITH.
